[57] **CLAIM**

The ornamental design for a cutting gauge for a chainsaw, as shown and described.

DESCRIPTION

FIG. 1 is an enlarged perspective view from below of the cutting gauge for a chainsaw of this invention, shown attached to a chainsaw with the chainsaw being represented by dashed lines;

FIG. 2 is a top plan view of FIG. 1;

FIG. 3 is a front elevational view of FIG. 1;

FIG. 4 is a right side elevational view of FIG. 1; and,
FIG. 5 is a bottom plan view of FIG. 1.

The rear elevational view and the left side elevational view are not shown as such views are substantially mirror images of FIGS. 3 and 4, respectively, and no additional information would be added by the inclusion thereof.

FIG. 2

FIG. 4

FIG. 5
